UNITED STATES PATENT OFFICE.

WILLIAM SCHMITZ, OF WATERBURY, CONNECTICUT.

MANTEL AND STOVE COMBINED.

SPECIFICATION forming part of Letters Patent No. 269,330, dated December 19, 1882.

Application filed January 9, 1882. (No model.)

To all whom it may concern:

Be it known that I, WILLIAM SCHMITZ, of Waterbury, in the county of New Haven and State of Connecticut, have invented an Improvement in Mantel and Stove Combined, of which the following is a specification.

The object of this invention is to obtain a stove adapted to heating or cooking, or both, and to render it ornamental and available as 10 a mantel, and at the same time protect the clothing from contact with the stove.

My improved stove is especially adapted to rooms which are used as cooking and sitting rooms, or those in which it is desirable to avoid 15 the loss of space occupied by a stove, and to use the same as a mantel or slab without injury from the heat of the stove.

In the drawings, Figure 1 is a vertical section of the stove and mantel. Fig. 2 is a sectional plan at the line x x . Fig. 3 is a sectional plan at y y , and Fig. 4 is a front elevation.

The stove portion is made of sheet or cast metal, and consists of a base, a , containing an 25 ash-drawer, b , supported on ways 1 1 , and having a top plate, c , with a central opening below the fire. The body of the stove h is oblong, and it is provided with the grate e , supply-door f , and one or more openings with covers in the top plate, g . There may be any suitable lining of fire-brick to the fuel-pot d , and the grate may be circular, so as to be shaken upon a central pivot, and the door f is sufficiently above the fire to allow of being used in 35 broiling food over the fire. Near one end of the stove h is a vertical flue, k , for the products of combustion to pass up into the horizontal flue l and return back by the second horizontal flue, m , and thence pass off at the 40 back of the pipe n to the chimney. There is an opening at n' into the lower side of the flue m , and a damper, 3 , by the opening of which the fumes from cooking on the stove will be drawn into the pipe m and taken to the chimney. 45

When this stove is to be adapted to baking, the fire is placed at one end, and there is an oven, as seen at p , with flues around it of the ordinary character, so that baking can be done 50 in this stove, as well as boiling and broiling.

The surrounding ornamental inclosure is

made to resemble a mantel, and the slab q may be of slate or any suitable stone.

The vertical angle-slabs r r and s s are preferably of stone, and so, also, is the vertical 55 front piece or lintel, q' , beneath the mantel q . These parts are put together by angle-irons and bolts, or in any suitable manner. The angle-slabs r r s s may rest at their lower ends upon the floor; but I prefer to employ the cast- 60 metal feet r' s' , as shown. The surfaces of the stone slabs may be plain, or more or less ornamented. There are open-work metal panels t at the ends, between the angle-slabs r and s . These may be hinged at the back edges, and 65 provided with a latch or fastening at the other edges, so to be swung open when desired.

The open-work metal doors u u in the front part of the case or inclosure are hinged upon the angle-slabs, or upon the angle-iron frame 70 for said slabs, and can be swung open to give access to the fire, or for cooking or baking.

The ornamental metal border at s^2 serves to strengthen the connections of the stone slabs and to ornament the casing. These parts are 75 bolted together by screw-bolts passing through the stone and metal at the required places and either screwing into the metal or provided with nuts.

There is a metal back plate at b' extending 80 all across the back, and there is an air-space between the same and the plate b^2 . This air-space opens at the top into the warm-air space between the horizontal plates b^3 and b^4 , so that heat will not pass to the wall behind the stove, but 85 the air will pass in below the lower edge of the plate b^2 , and also in through an opening in the plate b^2 behind the stove, and thence pass up and travel forward, coming out into the room through the upper part of the open-work doors. 90

The space between the horizontal plate b^3 and the under side of the mantel q is preferably filled, or partially so, with ashes or other non-conducting material to keep the mantel cool; but a water-box, b^5 , may rest directly 95 upon the plate b^3 , so that water may be warmed by the heated air, or by a pipe passing down to the stove, in which water circulates. The water may be admitted into this box by a cock and pipe from any suitable head and drawn 100 off by a faucet as required.

I make a sheet-metal casing, r^2 , inside the

angle-slabs s^2 , and this casing is open at both top and bottom, so that air may circulate upwardly between such casing and the angle-slabs to keep such slabs cool, and the said casing r^2 forms a shield to prevent the heat from the stove acting directly upon the slabs.

The panel s^3 in front of the ash-drawer is removable to give access to said ash-drawer. The panel should be hinged at one end, and 10 the slides upon which the ash-drawer rest are lower than the lower edge of the opening, so that the ash-drawer has to be lifted to remove it. This prevents dust being drawn out upon the slides as the drawer is moved.

15 This stove is to be distinguished from heaters that are set into a brick fire-place, because my improvement is complete in itself and portable, and may be set against a wall with safety because of the air spaces and flues through 20 which air circulates.

I claim as my invention—

1. The portable stove and mantel, in combination with the open-work front supporting the mantel, a plate below the mantel, non-conducting material between the same and the 25 slab, two or more metal plates with intermediate air-spaces behind the stove to protect a partition or wall, against which the mantel-stove may be placed, from heat, and a metal

plate and air-spaces below the stove, substantially as and for the purposes set forth. 30

2. The stove having a fire-pot and an opening in the top plate for cooking utensils, in combination with the ascending flue k , the connected horizontal flues l and m , having the 35 opening at n' for the escape of fumes from the cooking, and a damper, 3, for the same, substantially as set forth.

3. The combination, with the mantel-slabs q and the angle-slabs r^2 , of the open-work 40 metal doors between such angle-slabs, and a stove surrounded and protected by such slabs and iron work, substantially as set forth.

4. The combination, with the mantel q , the angle-slabs, and stove, of the mantel-casing r^2 45 inside the angle-slabs, for the purposes and substantially as set forth.

5. In combination with the mantel, the ornamental open-work inclosure and the stove within the same, a water-box beneath the mantel, and a filling of non-conducting material, 50 substantially as set forth.

Signed by me this 2d day of January, A. D. 1882.

WILLIAM SCHMITZ.
